UNITED STATES PATENT OFFICE.

GODFREY S. MAHN, OF PHILADELPHIA, PENNSYLVANIA.

DESIGN FOR A CIGAR-PROTECTOR.

43,151.

Specification for Design.

Patented Oct. 15, 1912.

Application filed March 15, 1912. Serial No. 684,003. Term of patent 14 years.

To all whom it may concern:

Be it known that I, GODFREY S. MAHN, a citizen of the United States, residing at the city of Philadelphia, in the county of Philadelphia and State of Pennsylvania, have invented a new, original, and ornamental Design for a Cigar-Protector, of which the following is a specification, reference being had to the accompanying drawings, forming part hereof, in which

tion of the coned extremital wall of the said protector having a beaded elliptical-shaped opening transversely arranged therein, and the same disclosing the particular design arrangement of the present cigar protector invention.

I claim:

The ornamental design for a cigar protector, as shown and described.

GODFREY S. MAHN.
